Attorneys.

UNITED STATES PATENT OFFICE.

PAUL RISSMAN, OF DETROIT, MICHIGAN, ASSIGNOR TO DETROIT INSULATED WIRE CO., OF DETROIT, MICHIGAN, A CORPORATION OF MICHIGAN.

MACHINE FOR COVERING CORD.

Application filed May 22, 1922. Serial No. 562,855.

To all whom it may concern:

Be it known that I, PAUL RISSMAN, a citizen of the United States of America, residing at Detroit, in the county of Wayne 5 and State of Michigan, have invented certain new and useful Improvements in Machines for Covering Cord, of which the following is a specification, reference being had therein to the accompanying drawings.

10. The invention relates to machines designed for the application of a tubular covering to flexible cords and it is the object of the invention to obtain a simple construction of mechanism by which a strip of 15 the covering material is automatically wrapped about and stitched to the cord to be covered. To this end the invention consists in the construction as hereinafter set forth.

20. In the drawings:

Figure 1 is a side elevation of the machine;

Figure 2 is a plan view thereof;

Figure 3 is a front elevation;

25. Figure 4 is a sectional elevation of the work feeding rolls;

Figure 5 is a cross-section on line 5—5 of Figure 4;

Figure 6 is an elevation of the feed rolls, 30 showing the relation of the same to the work and the sewing machine.

My improved machine comprises essentially means for continuously advancing the cord to be covered, together with a guide for 35 wrapping the covering strip about the cord, and a sewing machine for stitching the edges of the wrapped strip to each other. The sewing machine, which forms an element of my improvement, is of a well-known type comprising a base A, a pedestal B rising therefrom, a revoluble shaft journaled in said pedestal having a crank C at one end connected by a link D to an oscillatory shaft E journaled in the arm F 40 and having an oscillatory needle-carrying arm G at one end thereof. A segmental needle H is attached to the arm G and is actuated thereby. I is a loop carrier which is actuated from the crank C through an intermediate mechanism J such that a loop 45 is picked from the thread of the needle H and is transferred to produce a chain stitch. As the mechanism thus far described is not my invention and is of a

known type, it is believed unnecessary to 55 describe the same more in detail.

To apply the covering to the flexible cord, a strip of the covering material K is fed through a guide L in which it is wrapped completely around the cord M and has its 60 edge portions folded under, as indicated at N. Adjacent to the delivery end of this guide there is arranged a feed roll O upon a horizontally extending shaft P intermittently rotated by a ratchet wheel Q and 65 pawl R, which latter is actuated by an eccentric S upon the main drive shaft. The arrangement is such that the cord M, with the strip K wrapped thereabout, is drawn from the guide by the action of the feed 70 roll O, while the oscillation of the needle H and cooperation of the loop carrier I will stitch the two edges of the covering fabric to each other. These edge portions are held in contact with each other by a presser 75 finger T, which, however, is intermittently lifted to permit the needle H to pass through the fabric without interference.

The construction of the feed roll O is an 80 important part of my invention, in that it is adjustable to various sizes of work and in each adjustment will function to draw the cord with the cover wrapped thereabout out from the guide L. As specifically shown in Figures 4, 5 and 6, the shaft P 85 has formed thereon the toothed roll U, while upon opposite sides of this roll are sleeved the flanged rolls V and V'. These flanged rolls are fashioned to conform to the opposite sides of the cord and are 90 radially serrated, as indicated at W, so as to grip the fabric. Adjustment of the rolls V and V' is preferably accomplished by interiorly threading the same so as to engage with threaded portions X on the shaft 95 P, and set screws Y are provided for locking the flanged rolls in each position of adjustment.

In operation, the flanged rolls V and V' 100 are first adjusted to properly engage the fabric covered cord and are then locked by tightening set screws Y. The cord M is then fed into the guide and also the strip of the covering material is inserted and wrapped about the cord with its opposite 105 edges tucked under, as shown at N. Here the presser foot T will engage the folded edges to hold the same in contact with the

cord at the point where the stitching is to occur. When motion is imparted to the mechanism, the needle H will be rapidly oscillated and during each forward movement will pass through the looped edge of the cover on one side and upward through the looped edge on the other side. The thread thus carried through the fabric will be engaged by the loop carrier I, which will 10 throw the loop on the opposite side in a position to be in the path of the needle H during its next reciprocation. Thus the edges of the fabric will be stitched to each other, while the intermittent rotation of the roll O will advance the work as required.

Whenever it is necessary to adjust the machine for a larger or smaller cord, this may be accomplished by merely loosening the set screws Y and turning the flanged 20 rolls V and V' upon their threaded bearings until properly positioned. The set screws are then again tightened and the machine is in condition for operation.

What I claim as my invention is:

25 1. The combination with an oscillatory needle and cooperating loop throwing mechanism, of a guide for the cord to be covered, a surrounding guide for wrapping a fabric strip about said cord and feed mechanism comprising a roll having a serrated portion beneath the covered cord, radially serrated flanges on opposite sides of the cord, and means for adjusting said flanges to enlarge or diminish the width of the space there- 30 between.

2. The combination with an oscillatory needle and cooperating loop throwing mechanism, of a guide for the cord to be covered, a surrounding guide for wrapping a fabric 40 strip about said cord and turning under the edges of said strip, an intermittently rotated shaft extending beneath said cord adjacent to the delivery end of said guide,

a serrated portion on said shaft for engaging the bottom of the cord, and radially serrated side flanges arranged on opposite sides of the cord and adjustably secured to said shaft. 45

3. The combination with an oscillatory needle and cooperating loop throwing mechanism, of a guide for directing the cord to be covered beneath the path of said needle, a surrounding guide for wrapping a fabric strip about the cord and for turning the opposite edges of said strip under, a foot 50 for holding the turned edges of said strip adjacent to each other, and a feed roll comprising a serrated portion for engaging the bottom of the covered cord and radially serrated flanges on opposite sides of said cord, said flanges being adjustable towards and from each other to diminish or enlarge the space therebetween. 55

4. The combination with means for guiding a covering strip about a cord or rope, of means for uniting the edges of said covering strip, and feed mechanism for the covered cord comprising a roll having a serrated portion engageable with said cord, and a pair of radially serrated flanges adjustable to and from said serrated portion 70 for engagement with opposite sides of said cord.

5. The combination with means for guiding a covering strip about a cord or rope, of means for uniting the edges of said covering strip, and feed mechanism for the covered cord comprising a pair of coaxially rotative members serrated radially to their common axis and adjustable relatively in 75 the direction of said axis to oppositely engage said members with said cord. 80

In testimony whereof I affix my signature.

PAUL RISSMAN.
